(57) **CLAIM**

The ornamental design for a wind spinner, as shown and described.

DESCRIPTION

FIG. 1 is a perspective view of a wind spinner showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is an enlarged top view thereof;

FIG. 8 is an enlarged bottom view thereof;

FIG. 9 is an enlarged view thereof, taken from encircled portion 9 in FIG. 1; and,

FIG. 10 is an enlarged view thereof, taken from encircled portion 10 in FIG. 2.

The dot-dot-dash broken lines in the drawings are included to show a partially enlarged view only and form no part of the claimed design.

1 Claim, 10 Drawing Sheets
